CLAIM

The ornamental design for a support assembly for a grill as shown and described.

DESCRIPTION

FIG. 1 is a perspective view of our new design for a support assembly for a grill, in an expanded configuration;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view of a grill having our design, in a collapsed configuration;

FIG. 9 is a front elevation view of our new design for a support assembly for a grill, in the collapsed configuration;

FIG. 10 is a rear elevation view of our new design for a support assembly for a grill, in the collapsed configuration;

FIG. 11 is a left-side elevation view of our new design for a support assembly for a grill, in the collapsed configuration;

FIG. 12 is a right-side elevation view of our new design for a support assembly for a grill, in the collapsed configuration;

FIG. 13 is a top plan view of our new design for a support assembly for a grill, in the collapsed configuration; and,

FIG. 14 is a bottom plan view of our new design for a support assembly for a grill, in the collapsed configuration.

(Continued)

The portions of the support assembly for a grill shown in broken lines form no part of the claimed design. The broken line showing of a grill depicts environment and forms no part of the claimed design.
